UNITED STATES PATENT OFFICE.

THOMAS A. REID, OF WILKINSBURG, PENNSYLVANIA, ASSIGNOR TO WESTINGHOUSE ELECTRIC & MANUFACTURING COMPANY, A CORPORATION OF PENNSYLVANIA.

ELECTRIC FURNACE.

Application filed November 2, 1921. Serial No. 512,167.

To all whom it may concern:

Be it known that I, THOMAS A. REID, a citizen of the United States, and a resident of Wilkinsburg, in the county of Allegheny and State of Pennsylvania, have invented a new and useful Improvement in Electric Furnaces, of which the following is a specification.

My invention relates to electric furnaces and particularly to electric-resistance furnaces and it has for its object to provide a relatively simple resistor and resistor mounting for an electric-resistance furnace.

15 In practising my invention, I provide a relatively heavy and preformed resistor member comprising a plurality of end-connected convolutions, each having a plurality of oppositely offset or crimped portions in the plane of the convolutions. I provide a plurality of refractory supporting means, each having a plurality of slots of substantially T-shape adjacent to the inner faces thereof, within which the resistor member is 20 adapted to be located.

In the single sheet of drawings,

Figure 1 is a view, in lateral vertical cross section, of an electric furnace comprising the device embodying my invention, 30 taken on the line I—I of Fig. 2;

Fig. 2 is a view, in longitudinal vertical section of an electric-resistance furnace comprising the device embodying my invention, taken on the line II—II of Fig. 1;

35 Fig. 3 is an enlarged fragmentary view, in side elevation, of a refractory supporting means and associated resistor members, and

Fig. 4 is a view, in front elevation, of the members illustrated in Fig. 3.

40 An electric-resistance furnace 10 comprises a metallic framework or skeleton 11, a plurality of suitable supporting members 12, outer side walls 13, a floor 14 and a roof 15 which may be composed of a plurality of

45 bricks or blocks of any suitable heat-insulating material usually employed in the art. An inner lining 16 is composed of a plurality of bricks or blocks of any suitable high-temperature-resisting material usually

50 employed in the art to provide a furnace chamber 17 of any suitable or desired contour and dimensions.

Refractory resistor-supporting means 18 55 may severally comprise either a plurality of substantially rectangular bricks or blocks 19

mounted in recesses in the inner lining 16 and projecting into the chamber 17 or unitary resistor-supporting members of the desired lengths to conform to the corresponding dimensions of the linings 16 in which they are mounted. I have illustrated a plurality of bricks or blocks 19, each having under-cut side grooves 21 adjacent to their exposed faces. The exposed ends of the blocks are of less width than their body 60 portions in order that adjacent grooves 21 and the corresponding spaces between the exposed block ends may combine to form a slot 22 of substantially T-shape. If a single block is utilized as the resistor-supporting 65 member 18, a plurality of spaced slots 22, of substantially T-shape, are provided therein, substantially as hereinbefore described.

A resistor member 23 comprises a relatively heavy and unyielding bar, rod or tube 70 which is preformed to comprise a plurality of symmetrically spaced portions 24 which are crimped or offset from alternating portions 25. The resistor member is further formed to comprise either two substantially 75 parallel parts or a greater number of such parts or convolutions which may be integrally end-connected, the portions 24 being aligned laterally of the convolutions, as are 80 also the portions 25, all portions being located in the plane of the convolutions. The width of each portion 25 is substantially 85 equal to or slightly less than the width of the narrower part of each slot 22 and the width of each portion 24 is substantially the 90 same as the width of the wider portion of each of said slots. The refractory resistor-supporting members 19 are located in spaced-apart relation in the furnace and the resistor member 23 is of such area in lateral cross section as to be substantially self-supporting between the refractory resistor-supporting members. 95

When the resistor members 23 are located in one of the side walls it is desirable to provide means placed between those portions 24 located in the supports 19 to prevent accidental contact of the portions 25 between the supports. A relatively thin refractory plate 26 having substantially the same 100 length as the width of the member 19 and a width to fit closely between the portions 24 has its edges shaped to conform to the lateral contour of the resistor so that it may be 105 temporarily clamped between and supported 110

by two adjacent portions 24 during the installation of the resistor.

If it is desired to insert a resistor member in the supporting members, it is placed with the portions 25 in operative engagement with first the narrower and then the wider parts of the slots 22 in the supporting means 18, after which it is moved, in the longitudinal direction, until the more widely separated portions 24 are located in the wider portions of the slots and are held by the overhanging flanges. In order to remove a resistor member, the reverse operation may be employed.

15. The device embodying my invention provides a relatively simple preformed resistor member which is substantially self-supporting between the supporting members and may easily and quickly be mounted in, and 20 dismounted from, the supporting means in the furnace.

Various modifications may be made in the device embodying my invention without departing from the spirit and scope thereof and I desire that only such limitations shall be placed thereon as are imposed by the prior art or are specifically set forth in the appended claims.

19. I claim as my invention:—

20. 1. An electric furnace comprising a resistor having integral end-connected and substantially parallel-extending parts comprising oppositely offset portions.

25. 2. In an electric furnace, in combination, a resistor having a plurality of substantially parallel-extending integral parts, each part having portions offset in the plane of said parts.

30. 3. An electric furnace comprising a plurality of pairs of integral end-connected and substantially parallel-extending resistor parts having symmetrically spaced portions which are a greater distance apart than the other portions of said rods.

35. 4. An electric furnace comprising a resistor having substantially parallel-extending return-bent parts, each part having portions crimped in the plane of said return-bent parts.

50. 5. An electric furnace comprising a resistor having substantially parallel-extending return-bent parts, each part having symmetrically located portion oppositely offset in the plane of said return-bent parts.

6. In an electric furnace, in combination, 55 a plurality of relatively narrow, spaced refractory supporting members, each having a plurality of spaced slots, of substantially T-shape, in one face thereof, and a resistor member comprising integral end-connected substantially parallel-extending convolutions having portions located at different distances from each other, said resistor member being initially located in said slots in a position longitudinally displaced from its 65 operative position.

7. An electric furnace comprising a plurality of pairs of symmetrically and oppositely formed integral end-connected convolutions, the distance between said convolutions being recurrently variable. 70

8. In an electric furnace, in combination, a plurality of spaced refractory supporting members in said walls and extending into said chamber, each having a plurality of spaced slots, substantially of T-shape, in the portion extending into said chamber, and a resistor member having a plurality of integral substantially parallel-extending parts, 80 each part having portions oppositely offset in the plane of said parts, said oppositely offset portions lying in said slots of T-shape to maintain said resistor in operative position in said furnace chamber.

9. In an electric furnace, in combination, a plurality of walls enclosing a furnace chamber, a plurality of spaced, relatively narrow refractory resistor-supporting members extending into said chamber, each having a plurality of spaced slots, substantially of T-shape, in the portion extending into said chamber, and a relatively heavy resistor rod or bar having a plurality of integral substantially parallel-extending end-connected parts, each part having portions oppositely offset in the plane of said parts, said resistor member initially engaging said supporting members at its narrow portions and finally engaging said supporting members at its wider portions and being self-supporting between said refractory supports. 100

In testimony whereof, I have hereunto subscribed my name this 26th day of October, 1921.

THOMAS A. REID.
